DISPOSABLE WATER COLOR PALETTE

Tony F. Ferrucci, Seattle, Wash.

Application September 23, 1953, Serial No. 26,907

Term of patent 14 years

(Cl. D74—1)

To all whom it may concern:

Be it known that I, Tony F. Ferrucci, a citizen of the United States of America, residing in Seattle, county of King, and State of Washington, have invented a new, original, and ornamental Design for a Disposable Water Color Palette, of which the following is a specification, reference being had to the accompanying drawing, forming a part hereof.

Figure 1 is a top perspective view of a disposable water color palette, showing my new design.

Figure 2 is a plan view thereof.

Figure 3 is a transverse sectional view thereof taken on line 3—3 of Figure 2.

Figure 4 is a longitudinal sectional view thereof taken on line 4—4 of Figure 2.

I claim:

The ornamental design for a disposable water color palette, substantially as shown.
